UNITED STATES PATENT OFFICE

159,778

BROOCH OR SIMILAR ARTICLE

Herman Bogoff, Chicago, Ill.

Application April 19, 1950, Serial No. 9,327

Term of patent 7 years

(Cl. D45—19)

To all whom it may concern:

Be it known that I, Herman Bogoff, a citizen of the United States residing at Chicago, in the county of Cook and State of Illinois, have invented a new, original, and ornamental Design for a Brooch or Similar Article, of which the following is a specification, reference being had to the accompanying drawing forming part thereof, wherein—

Fig. 1 is a front elevation of a brooch or similar article, showing my new design; and

Fig. 2 is a bottom plan view thereof.

The essential features of my design for a brooch or similar article reside in the portions shown in full lines.

I claim:

The ornamental design for a brooch or similar article, as shown and described

HERMAN BOGOFF,
